UNITED STATES PATENT OFFICE.

JAMES R. MCWANE, OF BIRMINGHAM, ALABAMA, ASSIGNOR TO MCWANE CAST IRON PIPE COMPANY, OF BIRMINGHAM, ALABAMA, A CORPORATION OF ALABAMA.

MEANS FOR HANDLING AND MECHANICALLY RAMMING FLASKS.

Application filed December 12, 1924, Serial No. 755,509. Renewed October 2, 1928.

This invention relates to means for handling and mechanically ramming flasks for the manufacture of cast iron pipe or other analogous castings.

5 The primary object is to provide means for easily and quickly handling the excessively heavy cope and drag sections comprising the flasks used for this purpose, and to manipulate said sections in a manner to facilitate the 10 mechanical ramming of sand therein and thus, by the elimination of all laborious, expensive and time-consuming hand ramming operations, to increase production, produce more perfect output and materially decrease 15 the cost of production.

Another object is to provide means operable continuously along the entire length of a unit or section of the pipe foundry or other plant, said unit, which is known as a "bay", 20 being independent of other similar "bays", and capable of handling the copes and drags, by means of the improvements herein disclosed, receiving the same from pre-arranged longitudinal piles along the margins of the 25 "bay", automatically reciprocating them on molding machines beneath the sand impelling head of a sand slinging machine in a manner to receive the impelled sand uniformly throughout the length of the flask section, to 30 provide more perfect and more durable sand molds therein around the patterns, and then facilitating the removal of the finished cope or drag and the placement of the same in position upon the floor of the "bay", in closely 35 adjacent relation to the ramming means, to receive the cores and be locked together ready for the pouring operation.

A further object is to assemble the parts of the improved means for carrying out the 40 above-mentioned steps of the operation, so as to economize space, and to obviate the necessity for hauling the flask sections any appreciable distance, the empty flask sections being arranged in piles along either side and 45 close to the said reciprocating means, there being two of the latter, each having a molding machine in flanking relation to a centrally disposed sand-slinging machine, which is arranged to alternately operate on a cope or 50 drag section at one side or the other of the "bay", the space between the reciprocating means and in advance of the sand slinger being utilized for storing a continuous heap of 55 molding sand which is automatically taken up and deposited in the flask sections, while

the entire device is being slowly and continuously advanced, by mechanical means, into the sand heap, the finished flask sections being then removed from the molding machines and placed transversely and immediately in rear of the travelling ramming means in the space being constantly provided by said advance movement, on the floor of the "bay", which has been automatically cleaned of the sand, thus effecting a complete follow-up operation without loss of time or waste of space.

A full and complete understanding of the invention may be obtained from a consideration of the following detailed description, 70 taken in connection with the accompanying drawings forming a part of this specification, it being understood that while the drawings show a practical form of the invention, the latter is not to be confined to strict conformity with the showing thereof, but may be changed or modified, so long as such changes or modifications mark no material departure from the salient features of the invention, as specifically pointed out in the appended 80 claims.

In the drawings, in which similar reference characters designate corresponding parts throughout the several figures:—

Figure 1 is a plan view of a portion of a 85 unit or "bay" in a pipe or other foundry plant, the improved mechanical ramming means being shown in connection therewith.

Figure 2 is a side elevation thereof.

Figure 3 is a plan view, drawn on a larger 90 scale, of the right hand portion of the carriage for supporting the molding machine at one side of the "bay", and showing the means for reciprocating the same.

Figure 3^a is a similar view of the left hand 95 portion thereof, with the molding machine indicated in outline thereon.

Figure 4 is a detail plan view of a portion of the reciprocating means.

Figure 5 is a side elevation of the subject 100 matter of Figure 3.

Figure 5^a is a similar view of the subject matter of Figure 3^a.

Figure 6 is a longitudinal sectional view 105 illustrating the means for reciprocating the molding machines.

Figure 7 is an enlarged transverse sectional view through the main carriage, with the reciprocating molding machine thereon, and a flask section in position and fully rammed.

Figure 8 is an end view of the molding machine, with parts omitted and showing the manner of attaching the operating rams or pistons thereto.

In ramming flask sections by hand, as is ordinarily the custom in pipe foundries, it is necessary to have gangs of men, generally four, to ram or pack the molding sand in and around the pattern with hand tools, and in addition thereto, a number of shovels are necessary to supply the sand. This results in more or less confusion, the workmen being sometimes in each other's way, and is slow, expensive and laborious, often resulting in inferior molds, and such procedure also necessitates handling of the copies and drags by overhead lifting means to carry the same from the floor of the foundry to the molding machine, and thence back to the pouring floor.

These disadvantages are eliminated, in a great measure, by the employment of the herein-described improvements, which are primarily designed to be employed in connection with the improvements shown and described in my pending application for patent on a pipe foundry plant, filed May 12, 1923, Serial No. 638,639.

Referring to the drawings there is shown, in Figure 1, a portion of a pipe foundry unit or "bay", as defined between the upright I-beams or posts 1, which serve to support the roof. As shown in the said pending application, pairs of spaced rails 2 are properly set in the floor at a distance from the uprights to permit of the stacking of a number of copies or drags 3 therebetween, the said stacks consisting preferably of a plurality of all copies on one side of the "bay", and all drags on the other side, a space being left between the longitudinally disposed stacks for the passage of a workman. The flasks 3 may be of any desired type, but preferably of that type shown in the above-mentioned application and adapted to be used in connection with my multiple-lipped ladle.

The tracks 2 which extend from end to end of the "bay" are spaced apart a sufficient distance to allow the rammed flasks to be placed transversely therebetween, as indicated at 3^b, for the purpose of receiving the molten metal from the aforesaid ladle, and in order to support the said flasks, longitudinal sills 4, which may be formed of suitable wood, to avoid jarring the flasks when lowered, are suitably seated on the floor adjacent to the rails and extend from end to end of the "bay", the said sills receiving and supporting the flasks adjacent to their ends.

Continuous metal rack bars 5 are also suitably seated on the floor adjacent to the sills, the upper faces of the latter being somewhat higher than the teeth of the racks, so that the latter will not contact with the finished flasks. The racks are spaced apart a considerable distance for the reception of a continuous heap

5^a of molding sand, which has been properly treated to form a wet sand mold in accordance with the accepted method of making the same.

The tracks 2 at either side of the "bay" are adapted to carry identical combinations of mechanisms, and the same reference numerals will be applied to each. Mounted on each track 2 is a relatively long carriage 6, which may be formed of suitable angle irons or in any other desired manner, the showing of the carriages 6, as well as some other parts in Figure 1, being only in outline for the purpose of avoiding confusion.

Mounted on each carriage 6 is a molding machine 7, which is of substantially the same length as the flask sections 3 and slightly less than one-half the length of the supporting carriage 6 beneath, so that the said molding machines together with the flask sections may be readily reciprocated, by means to be later described, their full lengths upon said carriages, while the latter are, in turn, being slowly and continuously advanced along the tracks 2 by means also to be described.

A sand impelling machine 8 of a well known type and commonly known as a sand slinger is arranged transversely between the spaced, parallel carriages 6, and is rigidly secured to the latter by means of spacer blocks 9, which cause the said carriages and the sand slinging machine to move together along the tracks 2, the said machine being supported thereby in bridging relation to the space between the racks 5.

A power unit indicated at 10 is carried by the sand slinging machine, and includes a suitable motor for operating suitable gears confined in housings 11, and having meshing relation with the toothed racks 5 so that the connected parts may be slowly advanced along the tracks 2 in a direction towards the sand heap 5^a.

The sand slinger includes suitable, oppositely disposed worms 12, whose lower edges are located adjacent to the floor of the bay, and rotate in a direction to gather the sand and force the same towards the center of the machine, where it is taken up by an endless conveyor 13, and deposited upon an oscillating riddle 14, where it is screened, the sifted sand falling upon a chute 15, while the discarded part is passed through a chute 16. From the chute 15 the good sand falls into a hopper 17, thence to a conveyor 18 which is carried by a swingable arm 19, to a terminal head 20, which houses sand-impelling means driven at a high rate of speed and capable of impelling the sand in a thin stream and at high velocity in a downward direction to be directed where wanted by the hand of the operator grasping handle 18^a. The flexibility of the arm 19 and the connected parts, permits the said head 20 to be moved backwardly or forwardly towards the center of the sand slinger, or of being swung entirely across to

the other side of the same, for the purpose of alternately operating on flask sections at each side. The construction and operation of the sand slinging machine forms no part of the 5 present invention, but the combination of this type of machine, in connection with the aforesaid carriages and parts to be described, performs important functions of great value and advantage in foundries of this kind.

10 The molding machines 7 are provided with rollers or wheels 21, which are adapted to travel on rails 6^a carried by the carriages 6 (see Fig. 7), and the carriages 6 are, in turn, provided with suitable wheels 22 which ride 15 upon the aforesaid tracks 2, and it will thus be seen that the carriages may partake of a forward or backward movement along the tracks 2 while supporting the molding machines, and that the latter may partake of independent reciprocatory movement thereon.

In order to impart such reciprocatory movement to the molding machines, the carriages 6 carry elongated cylinders 23, suitably held at opposite ends of the carriage by 25 collars 24, or by any other desired means, as shown in Figures 3 and 3^a. The cylinders are oppositely disposed, and are arranged at opposite sides of the longitudinal axis of the carriage, the inner, open ends of the same being adjacent to each other and located at the center of the carriage, and being provided with glands 25 to prevent leakage of fluid under pressure around the extended ends of pistons or rams 26, which are adapted to be 35 forced their full lengths through the glands by the pressure of the fluid, when the latter is properly released.

The free ends of the pistons or rams 26 are connected to opposite ends of the molding 40 machine 7, at each side, by means of depending brackets 27, suitable nuts 28 being employed to secure the same. The brackets 27 include attaching plates 29 which are held by bolts 30 to the end walls of the said molding 45 machines, so that when pressure is allowed to enter one of the cylinders 23, the ram 26 is forced outwardly and the molding machine is moved in that direction, while the other attached ram is forced into its cylinder, there 50 being no pressure in the same. When the pressure is reversed, the reverse operation takes place, and the molding machine is moved in the opposite direction, as will be readily seen; and these operations, when continuously repeated at the desired speed under 55 control of the operator, results in the desired reciprocation of the molding machine, together with the superimposed flask section thereon, for the purpose of uniformly receiving the sand from the impelling head 20 throughout the length of the flask section.

60 The molding machine which may be of any suitable construction, though preferably of the type used in the before-mentioned application, includes depressible patterns 31 and a

stripping plate 32, the said patterns being controlled by a handle 33 for removal from the sand within the flask section 3^a, after the latter has been fully rammed and is to be removed from the molding machine, as shown 70 in Fig. 7, it being remembered that the molding machine is capable of forming the mold in either copes or drags, as the latter are identical in construction in all essential respects.

After a flask section, either cope or drag, is 75 placed in position on the molding machine, by a suitable overhead crane or other lifting device, and the same is clamped or hooked in position, the patterns are elevated by the lever 33. The operator then presses a push 80 button 34, mounted on a suitable upright 34^a in convenient reach at or near the center of the carriage 6 and which, by suitable wiring (not shown) starts a motor 35, forming part of a separate power unit for each side of the 85 bay, said power unit, in addition to the motor 35, including a centrifugal pump 36 driven by the motor and mounted on a supplemental car 37, having wheels 37^a adapted to ride on the tracks 2 and connected to the end of the 90 carriage 6 by suitable couplers 37^b, which causes each power unit to travel in unison with the carriages and the sand slinging machine.

Suitable fluid, either oil or water, passes 95 from the pump through a speed regulating valve 38, by means of the pipe 39 and into the main operating valve 40 which, through branch pipes 39^a leading to each cylinder 23, 100 controls the rams 26 alternately in the cylinders for moving the molding machine on that side backwardly and forwardly. At the end of the stroke of the molding machine, in either direction, suitable strikers 41, carried by the molding machine, are adapted to engage with a tappet arm 42 on a rod 43, which is mounted for sliding movement in guides 44 secured at intervals to the adjacent side of the main carriage 6, the said rod 43 extending to that end of the carriage which is connected to the car 37, where it is provided with a cross head 43^a, the ends of which slide upon spaced, parallel rods 43^b slidably mounted in guides 43^c carried by a control pilot valve 45, and mounted above and in communication with the main operating valve 40. The front ends of the rods 43^b, which lie at either side of the rod 43, are equipped with springs 43^d and adjusting nuts for cushioning the pull of the rod 43 on the pilot valve 110 actuating rods 43^b.

Local control of the stroke of the molding machines may be had through the medium of a hand lever 46 which normally stands upright adjacent to the push button support 34^a (Fig. 5), said hand lever 46 being intermediately pivoted to the side of the carriage 6, as at 47, and having a weight 48 at its lower end to hold the same upright. The rod 43 is provided at either side of the lever 125 130

46 with collars 49 adapted to be engaged by the lever 46 for shifting the rod 43 in either direction to manually effect the control valve in the same manner as the aforesaid automatically acting parts 41 and 42.

In order to effect control of the speed regulating valve 38 without the necessity of the operator leaving his position at the head of the sand slinging machine, an inclined shaft 10 50 is provided, having its front end mounted in a bearing 51 of an upright support 52, and having secured thereto a hand wheel 53 for turning the shaft. The rear end of the latter is mounted in a bearing forming part of 15 a housing 54 arranged above the valve 38, and provided on its terminal with a beveled gear 55, which is in mesh with a similar gear 56 mounted on the extended end of the stem 57 of the valve 38. By turning the hand wheel 20 53, the valve may be opened more or less from a remote point, and local variation of the speed of the reciprocating molding machine may be obtained to vary the hardness of the ramming of the sand within the flask section 25 mounted on the machine.

The thinner the layer of sand applied by the sand slinging machine, as produced by a faster passage of the flask section on the molding machine beneath the impelling head, and 30 the more passages thus required to produce the required filling, the harder the resultant packing or ramming of the sand within the flask section. This harder packing is desirable and necessary at the bell and spigot ends 35 of the mold to carry the weight of the core, while the intermediate portions of the mold may receive a softer ramming of the sand, which may be readily obtained by a slower 40 passage of the flask section beneath the head of the sand slinger. Such required variation of speed may be easily controlled by regulating the volume of fluid allowed to pass through the speed regulating valve 38 by the hand wheel 53. During the passages of the 45 flask beneath the impelling head, the latter may be readily moved from side to side of the center of the flask, so as to deposit the sand at all points along the sides of the patterns, although it is advisable to allow one complete 50 passage in one direction of the flask with the head depositing all the sand along one side of the pattern, and to shift the head for the entire reverse movement, and so on until the flask section is completely rammed.

55 From the foregoing it will be seen, especially by those skilled in the art of casting large bodies such as pipe or other elongated castings on a commercial scale, where economy of space is a most important consideration, and where rapidity and completeness of the cycle of operation is necessary, that the means herein shown and described have been 60 designed for the accomplishment of these purposes, and to effect the mechanical ramming of cope and drag sections of pipe mold-

ing flasks in an expeditious manner, thus obviating the necessity for the employment of gangs of hand rammers and shovels. The complete operations of ramming all the flasks in a given bay of the foundry are accomplished by a steady advance of the combined machines, starting at one end thereof and working along to the opposite end, while receiving the sections from the longitudinal piles at either side of the bay, reciprocating 70 the same beneath the thin spray of sand driven at high velocity into the innermost recesses of the flask and around the pattern the spray being readily guided and directed at the will of the operator. The heap of sand 75 when removed from the floor of the bay provides space at the rear of the travelling machine, after which the finished or rammed sections are lifted from the latter and placed transversely upon the floor of the bay immediately in rear of the machine. This results 80 in the greatest saving of time, labor and expense in the production of this class of castings.

85 What is claimed is:—

1. In combination, a carriage, a molding machine mounted on the carriage and movable longitudinally with reference thereto, means for longitudinally reciprocating the molding machine along the carriage, a sand slinging device arranged at one side of and connected to the carriage, said sand slinging device embodying means to cause the carriage to travel forwardly with said sand slinging device, the molding machine being 95 independently reciprocated beneath the discharge means of the sand slinging device.

2. In combination, spaced carriages, a molding machine mounted on each carriage and movable longitudinally with reference thereto, means for longitudinally reciprocating the molding machine along each carriage, a sand slinging device arranged between said carriages and connected thereto, said sand slinging device embodying means to cause the 100 carriages to travel forwardly with said sand slinging device, the molding machines being independently reciprocated beneath the discharge means of the sand slinging device.

3. A molding machine having a flask section thereon, a sand slinging device arranged at one side of the molding machine and adapted to impel sand into the flask, means for longitudinally reciprocating the molding machine beneath the head of the sand slinging device to cause a uniform deposit of the sand within the flask section, and means for varying the speed of reciprocation of said molding machine to vary the degree of hardness of the ramming of the sand.

4. A molding machine mounted on tracks and adapted to receive a flask section, a sand slinging device arranged at one side of the tracks and having means for impelling sand into the flask section, means for reciprocating 130

the molding machine longitudinally beneath the head of the sand slinging device, and means for causing the latter and the molding machine to advance together.

5. Spaced molding machines mounted parallel to each other for reciprocating motion, a sand slinging device arranged between the molding machines and having a swingable head provided with sand impelling means adapted to be moved over either of the molding machines, molding flasks removably mounted on the molding machines, means for independently reciprocating either or both of the molding machines, and means for causing the molding machines and sand slinging device to advance simultaneously.

6. In apparatus of the character described, means for mechanically ramming flasks comprising spaced pairs of parallel tracks, the space between said tracks providing for the reception of a sand heap, opposite carriages mounted to move along the tracks, a sand slinging device arranged between the carriages, a molding machine mounted on each of the carriages, a flask section removably mounted on each molding machine, means for independently reciprocating the molding machine together with the flask section in a longitudinal direction thereon, means to cause the sand slinging device together with the carriages and parts carried thereby to move slowly forward into the sand heap, and a swingable arm carried by the sand slinger and provided with a sand impelling head to 35 impel the sand into one or the other of the flask sections.

7. Means for mechanically ramming flasks, comprising spaced pairs of parallel tracks between which is placed a continuous heap of sand, carriages mounted to move along the tracks, a sand slinging device arranged between and connected to the carriages, longitudinal racks located between the pairs of tracks, gears carried and rotated by the sand slinging device and meshing with the racks to cause the sand slinging device and carriages to advance together towards the sand heap, molding machines mounted to be longitudinally reciprocated along the carriages and adapted to receive a flask, and means carried by the carriages and connected to the molding machines to independently reciprocate the same beneath the sand impelling head of the sand slinging device.

8. A flask ramming machine comprising opposite carriages adapted to move in unison along longitudinal tracks, a transversely-disposed sand slinging device carried by the carriages and having means for picking up sand from a pile and impelling the same through a movable head swingable over one carriage or the other, molding machines each having a flask section thereon and mounted to reciprocate its full length on the carriage, means carried by the latter for reciprocating the mold-

ing machines while the sand is being impelled into the flask, and means for propelling the sand slinging device, the carriages, molding machines and flasks slowly towards the continuous heap of sand to consume the same.

9. Means for mechanically ramming flask sections comprising spaced, parallel molding machines adapted to removably receive and hold either a drag or a cope section of a flask, and mounted for independent longitudinal reciprocation, carriages mounted to roll beneath and to support said molding machines, sand slinging mechanism arranged between and connected to the carriages and adapted to move therewith along the floor of the foundry, said mechanism including means for propelling the carriages in unison, for picking up sand between the same and for impelling said sand into either the drag or the cope section of the flasks at one side or the other, and means mounted on the carriages for independently reciprocating the molding machines a distance equal to their own lengths for uniformly receiving the impelled sand.

10. Means for mechanically ramming cope or drag sections of pipe molding flasks, comprising a molding machine adapted to receive the flask sections, a longitudinal carriage mounted on tracks and arranged beneath and adapted to support the molding machine, fluid compressing means carried by the carriage, a cylinder rigidly mounted on the carriage in connection with the compressor, and a piston mounted in the cylinder and connected to the molding machine for independently reciprocating the latter along the carriage.

11. Means for mechanically ramming cope or drag sections of pipe molding flasks, comprising a molding machine adapted to receive the flask sections, a longitudinal carriage mounted on tracks and arranged beneath and adapted to support the molding machine, fluid compressing means carried by the carriage, a cylinder rigidly mounted on the carriage in connection with the compressor, a piston mounted in the cylinder and connected to the molding machine for independently reciprocating the latter along the carriage, and a transversely disposed sand slinging device connected to the carriage and having means for automatically advancing itself together with the carriage to pick up sand from a pile and to impel the same into the flask section.

12. Means for the mechanical ramming of flask sections, comprising a carriage having wheels adapted to move along rails, a sand slinging device arranged at one side of the carriage, a fluid compressor mounted on the carriage, a pair of oppositely disposed cylinders mounted on the carriage and in connection with the compressor, a flask-receiving molding machine mounted on the carriage and having wheels adapted to permit independent reciprocation thereof, pistons mount-

ed in the cylinders and having their exposed ends connected to opposite ends of the molding machine, and means for automatically injecting fluid under pressure alternately into the cylinders to effect a regular reciprocation of the molding machine beneath the impelling head of the sand slinging device.

13. Means for the mechanical ramming of flask sections comprising a carriage, oppositely disposed hydraulic cylinders carried by the carriage and arranged longitudinally thereon, a supplemental car connected to the carriage and having a power unit and a fluid compressor thereon and having connection with said cylinders, a molding machine adapted to receive flask sections and mounted to reciprocate longitudinally on the carriage, oppositely moving and alternately actuated pistons mounted in the cylinders and connected at their free ends to the molding machine to cause its reciprocation, valve mechanism automatically actuated by the movements of the molding machine to control the alternate actuation of the pistons, and a sand slinging device having a sand impelling head to throw sand into the flask section while the molding machine is being reciprocated.

14. Means for dispensing with hand ramming of flasks in the manufacture of cast iron pipe or the like, comprising opposite molding machines having means for supporting a cope or a drag and for forming the mold therein, a wheeled carriage arranged beneath each molding machine to support the same, racks located adjacent to the tracks of the carriages, a sand slinging device mounted to

be self-propelled along said racks, means for connecting the carriages to the sand slinging device to cause the same to travel therewith, said carriages being longer than the molding machines to permit the latter to be longitudinally reciprocated thereon, cylinders oppositely disposed on said carriages, pistons mounted to be hydraulically actuated in the cylinders and having their outer ends connected to opposite ends of the molding machines to cause reciprocation thereof.

15. Mechanism for the mechanical ramming of flask sections, comprising a sand slinging device, a carriage movable on tracks at one side of said sand slinging device, a molding machine carried by the carriage, and mechanism for progressively moving the molding machine beneath the outlet of said sand slinging device and for varying the movement to modify the degree of hardness of the ramming.

16. Mechanism for the mechanical ramming of flask sections, comprising a sand slinging device, a carriage movable on tracks at one side of said device, said carriage being provided with tracks at the top, a molding machine provided with wheels mounted on the tracks of the carriage, and means carried by the carriage and connected with said molding machine for mechanically moving said molding machine on the carriage independent of the movement of the latter.

In testimony, that I claim the foregoing as my own, I have hereto affixed my signature.

JAMES R. McWANE.
